[57] CLAIM

The ornamental design for a handle for a fountain brush
or the like, as shown and described.

DESCRIPTION

FIG. 1 is a perspective view of a handle for a fountain
brush or the like, showing our new design;

FIG. 2 is a top plan view thereof;

FIG. 3 is a side elevational view thereof;

FIG. 4 is a bottom plan view thereof;

FIG. 5 is a front end elevational view thereof; and,

FIG. 6 is a rear end elevational view thereof.

In FIGS. 2-4, the handle rod has been shown fragmentarily
for ease of illustration.

FIG. 2

FIG. 3

FIG. 4

FIG. 5

FIG. 6
